(57) **CLAIM**

The ornamental design for a charging station for electric vehicle, as shown and described.

DESCRIPTION

FIG. 1 is a front elevation view of a charging station for electric vehicle showing my new design;

FIG. 2 is a left side elevation view thereof;

FIG. 3 is a top, front, left side perspective view thereof;

FIG. 4 is a top, front, left side perspective view thereof; and,

FIG. 5 is a top plan view thereof.

The broken lines in the drawings depict portions of the charging station for electric vehicle that form no part of the claimed design.
